UNITED STATES PATENT OFFICE.

JOHN FERREOL MONNOT, OF NEW YORK, N. Y., ASSIGNOR TO DUPLEX METALS COMPANY, OF NEW YORK, N. Y., A CORPORATION OF NEW YORK.

PROCESS OF AND APPARATUS FOR CUTTING COMPOUND METAL ARTICLES.

973,376.

Specification of Letters Patent.

Patented Oct. 18, 1910.

Application filed March 2, 1908. Serial No. 363,916.

To all whom it may concern:

Be it known that I, JOHN FERREOL MONNOT, a citizen of the United States, residing at New York, in the county of New York and State of New York, have invented certain new and useful Improvements in Processes of and Apparatus for Cutting Compound Metal Articles; and I do hereby declare the following to be a full, clear, and exact description of the same, such as will enable others skilled in the art to which it appertains to make and use the same.

My invention relates to processes of and apparatus for severing or cutting compound metal articles comprising a base of one metal and a covering or coating of an unlike metal welded thereto, said apparatus being designed not merely to sever or cut off plates and other articles of compound metal such as specified, but also to draw the coating over the severed edges so as to protect the same.

My invention consists in severing means comprising one or more blunt or obtunded tools (using the term "obtunded" as distinguished from "edged" or "cutting"), such blunt or obtunded tools acting by what may be best described as a drawing or pinching action, as distinguished from a cutting action, whereby the relatively ductile coating of the object being severed is not cut immediately before the base metal below it is acted upon by the tool (as would be the case if sharp or cutting tools were used), but to the contrary the coating remains intact until the plate or other object is very nearly severed, being drawn down over the edge as the operation goes on, so that the coating is not severed until at or very near the very last; and my invention also consists in the described process or method of severing the compound articles and drawing the coating over the severed edge. In the following description I shall at various times speak of the severing of plates and the like by these obtunded tools as a "cutting" of the plate or other object; but this I do merely for convenience and because there is no other convenient term to express the idea of trimming or otherwise severing off parts of the plate or other object to reduce it to a desired shape or thickness; the term "cutting" being then used in its broadest sense, in which it does not necessarily imply the action of what are commonly called "cutting" tools.

My invention consists further in a succession of such blunt or obtunded tools arranged to effect the cutting off in successive stages; in means for compacting the layer or layers of the coating metal on the cut edge; and in other features of invention more fully hereinafter set forth and pointed out in the claims.

Compound metals such as are referred to above, comprise a core or base of one metal (which is usually a relatively strong and cheap metal, such as iron or steel), and a covering or coating for one or both surfaces of such core or base metal of an unlike metal (usually one which is weaker, but more malleable or ductile, and often one which is much more expensive); and in most cases, the core or base metal is one which is relatively subject to oxidation or other chemical attack, and the coating metal is one which is relatively little subject to chemical attack. The coating, being dense, impervious, and welded to the core or base at all points, effectively prevents chemical attack of such base. An example of a compound metal such as referred to is a metal comprising a base of steel, either soft or hard, and a coating welded thereto of copper, aluminum, aluminum bronze, the various alloys termed bronze generically, brass, silver, etc. Compound metals such as referred to may be produced by the process described in my Letters Patent Nos. 851,684, dated April 30th, 1907 and 853,716 dated May 14th, 1907, and in my application Sr. No. 281,680. One of the prime objects of the coating being to protect the base or core from chemical attack, it is highly important that when forming articles from sheets, bars, tubes or the like of such metals, the coating shall be drawn over the edges of the article formed, so as to protect said edges as well as the faces of the article. Obviously this cannot be done by an ordinary cutting operation, for a cutting tool proper would sever the coating before severing the base metal. I have found, however, that the desired object may be accomplished by the use of one or more drawing or pinching tools, which operate in fact by drawing or pinching off the sheet, bar, tube or the like, so that said sheet or other article is reduced in thickness under the tools to substantially the point of severing before the coating is ruptured. In fact the base metal is usually severed before the

coating. By this means the coating covers completely, or nearly completely, the entire thickness of the severed edge of the article, and if a thin strata of uncovered base metal 5 remains, a simple smoothing down or burnishing of the edge will completely close down the coating over the severed edge and compact it so as to leave no crevice permitting entry of corrosive gases or liquids and 10 chemical action on the base metal beneath. The importance of so protecting the edges of compound metal articles such as compound metal ship plates, roofing plates, boiler plates and other compound metal articles 15 which in ordinary use are exposed to chemical attack, will be seen readily. Ship plates, particularly those of vessels navigating salt water, are not only exposed to oxidation, but to electro-chemical action resulting 20 from the presence of sodium chlorid and other salts in the water; and such electro-chemical action might be very destructive if the coating were not drawn over the edges of the plates, so as to prevent the water from 25 reaching the iron beneath. Similarly, roofing plates are frequently exposed to corrosive fumes, as for example, sulfurous acid fumes and carbonic acid fumes of coal smoke, which attack steel surfaces rapidly, 30 while having practically no effect on copper; and steel boiler plates, and boiler tubes, are exposed to corrosive, pitting and similar destructive actions, which may be obviated entirely by employing plates coated on all 35 points subject to attack with an impervious coating of copper. It will be understood that electro-plated coatings are not impervious; but coatings applied as described in my Patents Nos. 851,684 and 853,716 and my 40 said application Sr. No. 281,680 are absolutely impervious to liquids and gases, even when the coatings have been reduced by extension to extreme thinness.

The objects of my invention are, therefore, 45 to provide a method of protecting the cut or severed edges of articles formed of compound metals (using the term "cut" in the sense heretofore defined;) and to provide simple, efficient and economical apparatus 50 for drawing the coating over the cut edges.

I will now proceed to describe my invention with reference to the accompanying drawings, in which certain forms of apparatus capable of performing the described 55 process are illustrated more or less diagrammatically, and will then point out the novel features in claims.

In the said drawings:—Figure 1 shows a transverse sectional elevation of one form 60 of apparatus embodying my invention, and Fig. 2 shows a side view thereof without the traveling carriage for the work. Figs. 3-11 inclusive illustrate diagrammatically and in section, means and materials used in this 65 method of operation, it being understood

that these views are diagrammatic in their nature and are not intended to be exact as to form and proportion. Fig. 3 shows a section of a compound metal plate coated on both sides; Fig. 4 the first stage in the cutting thereof; Fig. 5 a further stage in the cutting thereof, and Fig. 6 the cut sheet with the coating drawn down over the cut edge and compacted as hereinafter described. Figs. 8, 9 and 10 show in section portions 70 of obtunding tools spaced to perform the operations of Figs. 4, 5 and 6 respectively. Figs. 7 and 11 are views, similar to Figs. 6 and 10 respectively, illustrating the action of the alternative form of apparatus shown 80 in Fig. 12. Fig. 12 shows a side view of a form of apparatus alternative to that shown in Figs. 1 and 2.

Referring now to the accompanying drawings, and at first to Figs. 1 and 2 thereof, said apparatus comprises a plurality of obtunding rotary tools, 1, 1, 2, 2, and 3, 3, arranged in pairs and spaced apart different distances, as illustrated. These tools are mounted upon shafts 4, 4, the upper shafts 90 mounted in vertically adjustable bearings 5, 5, provided with adjusting screws 6, 6, or equivalent means for adjusting said shafts vertically. Any one of the said shafts, as for example the lower shaft of rolls 1, 1, 95 may be provided with a driving wheel 7; and from said lower shaft motion is communicated through gear wheels 8 to the corresponding upper shaft, the design of the gearing being such as to permit some vertical movement of the upper roll without throwing the gears out of mesh or out of action. The shafts of each of the other pairs of rolls are similarly connected by gearing, and motion is communicated from one pair of shafts to another by means of intermediate gears 9, shown in dotted lines in Fig. 2, carried by adjustable supports 10 similarly shown. This construction will be 100 obvious to those skilled in the art. In many cases, particularly for the smaller sizes of machines, no support for the work is necessary, the work being held in the hand while it is passed through the rolls; but I have indicated a support for the work, comprising 105 a sliding table 11, arranged adjacent to the rolls or tools 1, 2 and 3.

In the operation of this apparatus, rolls 1, 2 and 3 will be adjusted progressively closer together. The sheet or other object 110 to be cut first encounters rolls 1, and is grooved thereby, without severing of the coating, as indicated in Fig. 4; the sheet next passes between rolls 2 and is still further grooved thereby, still without severing of 115 the coating, as indicated in Fig. 5; and finally the sheet will pass between rolls 3, which are still closer together; and by these rolls the sheet will be severed, as indicated 120 in Fig. 6. In these successive operations 125

- the coating has been drawn over the edge formed by the rolls, so that upon the final severing of the sheet the coating substantially covers said edge. For many purposes 5 no further treatment of the edge may be necessary; but in some cases the edge may be left somewhat rough, or it may be desirable to compact the two layers of coating metal where they meet, and for this purpose 10 I may employ a smoothing or burnishing or spinning tool, which may consist of a simple revolving disk 12, shown in Fig. 2, driven by suitable gearing, and arranged to rotate against the severed or cut edge of the 15 work, and thereby to press together the metal of the coatings, and by a spinning or burnishing action compact them into one impervious coating.

It will be understood that I may use a 20 still greater number of pairs of cutting rolls than indicated in Fig. 2, or a less number as may seem desirable. It is not necessary in all cases to use a plurality of pairs of rolls and in my application Sr. No. 293,410 25 above mentioned I have illustrated an apparatus for cutting off relatively thin sheets of compound metal, comprising only a single pair of rolls, which rolls are arranged to draw down the material of the coating 30 over the cut edge, in the manner above described.

In Figs. 3 to 7 inclusive 13 designates the base metal and 14 the coating or coatings.

In Figs. 8, 9, and 10 I have indicated 35 somewhat exaggerated, the section of the edges of the cutters. As will be seen, these edges are V shaped and are quite blunt or round at their apices, so that the tools are in no strict sense cutting tools but rather operate by drawing or pinching the metal.

In Fig. 12 I have indicated an apparatus similar to that shown in Figs. 1 and 2, except that the rolls are not arranged in pairs, but work in coöperation with the table or 45 support for the material to be cut.

It will be obvious that in the case of apparatus for cutting tubing or curved sheets, the rolls may be arranged about a common center, instead of in a straight line as indicated in Fig. 2.

What I claim is:—

1. Apparatus for cutting compound metal and for covering over the cut edges, comprising an obtunding rotary cutter having a blunt cutting edge in the plane of rotation, means for driving the same and means for holding the work against such cutter.

2. Apparatus for cutting compound metals and for covering over the cut edges, comprising a pair of obtunding rotary cutters, each such cutter having a blunt cutting edge in the plane of rotation, such edges of each pair of cutters arranged in coöoperative juxtaposition, and means for driving the cutters.

3. Apparatus for cutting compound metals and for covering over the compound edges, comprising a plurality of rotary obtunding cutters arranged in succession and set to cut deeper depths progressively, each such cutter having a blunt cutting edge in the plane of rotation, means for holding the work against such cutters and means for driving said cutters.

4. Apparatus for cutting compound metals and covering over the cut edges comprising a movable support for the work, a rotary obtunding cutter having a blunt cutting edge in the plane of rotation arranged in coöoperative juxtaposition to said support and means for driving the cutter.

5. The process of cutting hard metal bodies covered with softer metals and of covering the cut edges of the hard metal with the softer metal which consists in cutting said bodies by a rupturing pressure exerted by a rounded or obtunding edge tool.

6. The process of cutting hard metal bodies covered with softer metals and of covering the cut edges of the hard metal with the softer metal which consists in passing a plate of such joined metals between a pair of obtunding cutters engaging said plate from opposite sides under sufficient pressure to pinch off the stiffer metal and flow the softer metal over the edge exposed thereby.

7. The process of cutting and protecting the cut edges of hard metal bodies having a covering of softer metal, which consists in severing such a covered body without shearing by pinching or drawing down the thickness of the harder metal body by pressure applied along the line of cut through the said coating until the hard metal ruptures, and after it the softer metal, thereby drawing down the softer covering metal over the cut edge, and then compacting the soft metal so drawn over the cut edge.

8. The process of cutting and protecting the cut edges of hard metal bodies having coverings of softer metal on opposite sides thereof, which consists in severing such a covered body without shearing by pinching or drawing down the thickness of the harder metal body by pressure applied through said coatings on both sides along the line of cut until the hard metal ruptures, and after it the softer coverings, thereby drawing down the softer metal coverings over the cut edge.

9. The process of cutting and protecting the cut edges of hard metal bodies having coverings of softer metal on opposite sides thereof, which consists in severing such a covered body without shearing by pinching or drawing down the thickness of the harder metal body by pressure applied through said coverings on both sides along the line of cut until the hard metal ruptures, and after it the softer coverings, thereby drawing down

the softer metal coverings over the cut edge, and then compacting the soft metal so drawn over the cut edge.

10. The method of forming plated articles which consists in first pressing in the surface of an exteriorly plated blank in such manner as to draw the plated portion into the depression thus formed, and finally separat-

ing the article from the blank at the base of the depression. 10

In testimony whereof I affix my signature in the presence of two witnesses.

JOHN FERREOL MONNOT.
